UNITED STATES PATENT OFFICE.

JACOB DIEHL, OF CLEVELAND, OHIO, ASSIGNOR TO THE STANDARD SEWING MACHINE COMPANY, OF CLEVELAND, OHIO, A CORPORATION OF OHIO.

TAKE-UP FOR SEWING-MACHINES.

946,019.

Specification of Letters Patent. Patented Jan. 11, 1910.

Application filed July 2, 1907. Serial No. 381,861.

To all whom it may concern:

Be it known that I, JACOB DIEHL, citizen of the United States, and resident of Cleveland, in the county of Cuyahoga and State 5 of Ohio, have invented certain new and useful Improvements in Take-Ups for Sewing-Machines, of which the following is a specification.

My present invention relates particularly 10 to improvements in that type of take-up mechanism in which a take-up lever is fulcrumed on a movable or swinging support and actuated from a rotating crank; such 15 type of take-up mechanism being desirable in that the use of cams and the objectionable wear and friction incident thereto is avoided. In this type of take-up mechanism, the take-up lever is usually connected directly to a 20 crank-pin which is fixedly attached to the actuating crank and therefore movable in a path concentric with the axis of the crank. I have found in practice, however, that a 25 take-up lever so connected and operated does not coöperate with the other stitch-forming elements of a rotary shuttle sewing machine, in a manner to control the thread with that degree of nicety necessary to produce the most desirable stitching.

It has therefore been the object of my 30 present invention to improve such type of take-up mechanism with a view to adapting it to more completely controlling the thread during the stitch-forming operation and thereby producing improved stitching.

To this end, my invention consists in the 35 novel features of construction and combinations of parts hereinafter set forth in detail and pointed out in the appended claims.

Referring now to the accompanying drawings 40 forming part of this specification, and in which I have shown only so much of a sewing machine as is necessary to illustrate my invention, Figures 1 to 5 inclusive are front end views of a part of the machine, 45 with the face-plate removed from the arm thereof, showing the relative positions of the needle, shuttle, and take-up at different times during the formation of a stitch. Fig. 6 is a side elevation of the parts in the position shown in Fig. 3, with the arm in vertical section to more clearly show the connection between the needle-bar and the take-up and their actuating crank.

Similar reference characters designate cor- 50 responding parts in the several figures of

the drawings, in which the frame of the machine comprising the bed-plate 1 and overhanging bracket-arm 2, the driving shaft 3 with its attached crank 4, the needle-bar 5 with its attached needle 6, and the rotary shuttle 7, are all of usual construction and operation as found in the "Standard" sewing machine. Also as in said "Standard" and other similar machines, the needle-bar 5 is actuated from the crank 4 in the 60 usual manner by means of a pitman 8 which connects with a pin 9 at the upper end of the needle-bar and with a crank-pin 10 on the crank 4.

In take-up mechanism of the type embodying my present invention, the take-up lever, as hereinbefore mentioned, is generally connected directly to a crank-pin which is rigidly attached to the actuating crank and therefore movable in a path concentric with the axis of said crank. In accordance with my present invention, however, the pitman 8 connecting the crank and needle-bar is formed with a rigid arm or extension 11 for the connection therewith of 70 the take-up lever, which arm or extension at its end or point of connection with the take-up lever will be caused to move in the path of an ellipse, as indicated by dotted lines, and therefore in a path eccentric to 75 the axis of the crank-pin rather than concentric with it. This change in the path of movement of the take-up lever actuating device from a circular path concentric with the axis of the crank, as heretofore, to an 80 elliptical path eccentric to the axis of the crank, results in a movement of the take-up lever such as will cause it to accurately and 85 completely control the thread in coöperation with the needle and shuttle in a manner as 90 will presently be described.

The take-up lever, indicated at 12, is substantially straight and is pivotally connected at its inner end to the pitman extension 11 and at its outer end is provided with a 100 thread-receiving eye. At a point between its ends this take-up lever is pivotally connected with one end of a link 14 which at its opposite end is mounted on a stationary pivot 15; this link being coöperative with the pitman extension 11 in supporting the take-up lever and controlling the movement 105 of the same.

The action of the take-up in coöperation 110 with the needle and shuttle in controlling

the thread is shown in Figs. 1 to 5 inclusive. In Fig. 1 the thread-engaging end of the take-up is at substantially its lowest point preparatory to drawing up the thread 5 loop just being cast off by the shuttle. From the position shown in Fig. 1 the take-up moves upwardly in drawing up the thread to the position shown in Fig. 2, and from thence to the position shown in Fig. 3; the 10 movement of the take-up from the position shown in Fig. 2 to that shown in Fig. 3 being upwardly and laterally in the arc of a relatively large curve and thereby operating to tighten the stitch gradually and 15 produce an elastic formation of the same, as is very desirable. From the position shown in Fig. 3 to that shown in Fig. 4 the take-up moves downwardly in substantially the same time as the needle and 20 gives down just enough thread as is required by the needle without the formation of any undue slack. At the time the take-up reaches the position shown in Fig. 4, the needle has reached its lowest limit of movement 25 and is about to ascend to throw out the thread loop to be entered by the shuttle. The thread required for the formation of this loop is provided by the take-up in its continued downward movement from the 30 position shown in Fig. 4 to that shown in Fig. 5. From the latter position to that shown in Fig. 1 the take-up further continues its downward movement to provide the necessary thread required by the shuttle 35 in carrying the thread loop therearound, and moves in such time relatively to the shuttle as to provide the required length of thread without the formation of any undue slack. When the parts reach the position 40 shown in Fig. 2 the shuttle is about to cast off the thread loop and the take-up about to begin its upward movement to draw up said cast-off loop and complete the stitch.

45 The pitman 8 with its arm or extension 11 constitutes a pitman-lever and is so designated in the following claims.

What I claim is:

1. In a sewing machine, the combination of 50 a rotary driving crank, a reciprocatory needle-bar, a take-up lever, a pitman-lever connected at a point between its ends with the crank and at its opposite ends with the needle-bar and take-up lever respectively, 55 and a bodily movable fulcrum carrying the take-up lever at a point between its ends, the several said parts being organized and operative to move the thread-engaging end

of the take-up lever in the arc of a relatively large curve during the stitch-tightening operation and thereby produce an elastic formation of stitch. 60

2. In a sewing machine, the combination of a rotary driving crank, a reciprocatory needle-bar, a take-up lever, a pitman-lever 65 connected at a point between its ends with the crank and at its opposite ends with the needle-bar and take-up lever respectively, and a link connected at one end to a stationary pivot and at its opposite end to the 70 take-up lever and being co-operative with the pitman-lever, the several said parts being organized and operative to move the thread-engaging end of the take-up lever in the arc of a relatively large curve during the stitch- 75 tightening operation and thereby produce an elastic formation of stitch.

3. In a sewing machine, the combination of a rotary driving crank, a reciprocatory needle-bar, a substantially straight take-up 80 lever, a pitman-lever connected at a point between its ends with the crank and at one end having connection with the needle-bar and at its opposite end having connection with one end of the take-up lever, and a piv- 85 oted link connecting with the take-up lever at a point between its ends, the several said parts being organized and operative to move the thread-engaging end of the take-up lever in the arc of a relatively large curve during 90 the stitch-tightening operation and thereby produce an elastic formation of stitch.

4. In a sewing machine, the combination of a rotary driving crank, a reciprocatory needle-bar, a take-up lever, a pitman-lever 95 connected at a point between its ends with the crank and at one end having connection with the needle-bar and at its opposite end having connection with one end of the take-up lever, and a link connected at one end to 100 a stationary pivot and at its opposite end connected to the take-up lever at a point between its ends, the several said parts being organized and operative to move the thread-engaging end of the take-up lever in the 105 arc of a relatively large curve during the stitch-tightening operation and thereby produce an elastic formation of stitch.

Signed at Cleveland, in the county of Cuyahoga, and State of Ohio, this 17th day 110 of June, A. D. 1907.

JACOB DIEHL.
